(57) **CLAIM**

The ornamental design for a red light therapy device, as
shown and described.

DESCRIPTION

FIG. 1 is a front, top, and right perspective view of a first
embodiment of a red light therapy device showing my new
design;

FIG. 2 is a rear, bottom, and left perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 2;

FIG. 11 is a front, top, and right perspective view of a second
embodiment of a red light therapy device showing my new
design;

FIG. 12 is a rear, bottom, and left perspective view thereof;

FIG. 13 is a front elevational view thereof;

FIG. 14 is a rear elevational view thereof;

FIG. 15 is a left side elevational view thereof;

FIG. 16 is a right side elevational view thereof;

FIG. 17 is a top plan view thereof;

FIG. 18 is a bottom plan view thereof;

FIG. 19 is an enlarged view of portion 19 shown in FIG. 11;

FIG. 20 is an enlarged view of portion 20 shown in FIG. 12;

FIG. 21 is a front, top, and right perspective view of a third
embodiment of a red light therapy device showing my new
design;

FIG. 22 is a rear, bottom, and left perspective view thereof;

FIG. 23 is a front elevational view thereof;

FIG. 24 is a rear elevational view thereof;

FIG. 25 is a left side elevational view thereof;

FIG. 26 is a right side elevational view thereof;

FIG. 27 is a top plan view thereof;

FIG. 28 is a bottom plan view thereof;

FIG. 29 is an enlarged view of portion 29 shown in FIG. 21;

and,

(Continued)

FIG. 30 is an enlarged view of portion 30 shown in FIG. 22. The dash-dash broken lines in the drawings depict portions of the red light therapy device that form no part of the claimed design. The dot-dash broken lines represent boundaries of the enlarged portion that form no part of the claimed design.
